UNITED STATES PATENT OFFICE

WESLEY JOHN SHAW, OF HAVERHILL, MASSACHUSETTS, ASSIGNOR TO NEW ENGLAND WOOD HEEL CO., OF HAVERHILL, MASSACHUSETTS, A CORPORATION OF MASSACHUSETTS

MACHINE FOR CONCAVING WOOD-HEEL BLOCKS

Application filed October 14, 1926. Serial No. 141,479.

The present invention relates more particularly to machines for concaving wood-heel blocks, though certain features thereof are of more general application. Concaving machines are not broadly new. One such machine, for example, is disclosed in the patent to Day, No. 796,194, granted August 1, 1905. Present-day machines, however, have certain defects which it is the chief object of this invention to overcome.

The nature of the improvements introduced by the present invention will be made clear in connection with the accompanying drawings, in which Fig. 1 is a plan of a machine constructed according to a preferred embodiment of the invention; Fig. 2 is a vertical section taken upon the line 2—2 of Fig. 1, looking in the direction of the arrows; Figs. 3 and 4 are vertical sections taken upon the lines 3—3 and 4—4, respectively, of Fig. 1, looking in the directions of the arrows; Fig. 5 is a front elevation of the machine, with parts broken away, for clearness; Fig. 6 is a vertical section taken upon the line 6—6 of Fig. 1, looking in the direction of the arrows; Fig. 7 is a section taken upon the line 7—7 of Fig. 3, looking in the direction of the arrows; and Fig. 8 is a side elevation of the parts shown in Fig. 7.

As is explained in the above-mentioned patent, a heel block 2 is clamped between jaws 4 and 6 of a heel-block holder and advanced towards a concaving cutter 8. The cutter cuts a concave groove in the top of the heel block. The concave groove is completed in two operations. During the first operation, the heel-block holder is advanced towards the cutter along a path such that one side only of the top of the heel block shall become concaved. In Fig. 1, the side 10 of the heel-block top is shown acted on by the cutter. During this first operation, the carriage upon which the heel-block holder is carried is guided in its movement by a cam 12 that engages an adjustable guide roll 14. The carriage is returned toward the left, as viewed in Fig. 1, and then again advanced toward the right. During this second operation, however, the carriage is guided by a cam 16 that engages an adjustable guide roll 18, with the

result that the opposite side 20 of the top of the heel block becomes acted upon by the cutter. During its first operation, the cam 12 of the carriage is maintained in engagement with the guide roll 14 by a cam 22 that engages an arm 24 of a bell-crank lever to force the other arm 26 against a roll 28 of the carriage. During the second operation, the cam 16 of the carriage is maintained in engagement with the guide roll 18 by a cam 30 that engages an arm 32 of a bell-crank lever to force the other arm 34 against a roll 36 of the carriage. The cams 22 and 30, that thus cause the carriage to oscillate transversely back and forth before each forward movement towards the cutter, are mounted on a shaft 38. The bell-crank levers are returned to normal position, when removed from the influence of the cams 22 and 30 by springs 40. The carriage oscillates about a pivot 42, shown in the said patent at e'. The pivot 42 is substantially fixed in position, but the carriage is slidable with respect to this substantially fixed point. It will be unnecessary to describe this operation in greater detail as it is fully described in the said patent, and is well known in the art.

As the shape and the depth of the required concavity varies in different heels, provision is made for adjusting the position of the heel block relatively to the cutter. This provision takes the form of a screw 44 (shown in the said patent at f') that is pivotally connected with one end of the carriage at 46. The carriage is slidable with respect to the pivot 46. The screw 44 is vertically adjustable in a lug 48 of the frame of the machine to effect the raising and the lowering of the said end of the carriage about a pivotal shaft 50. This adjustment permits the heel to be presented to the cutter in varying angular positions, but the degree of adjustment is very slight. A greater angular adjustment is shown in the drawings about a pivot 52. The jaws 4 and 6 are pivotally mounted at 54 and 56, respectively, on a support 58 that is adapted to be pivotally adjusted about the pivot 52 by a threaded rod 60. The rod 60 is threaded in a yoke 62 that is provided with openings 64 and 66 through which extend rods 68 and 70,

respectively, of the heel-block clamp. The rod 60 is swiveled in a pin 72 (shown more particularly in Fig. 6) that is rockably mounted in ears 74 that project downward from the support 58. The free end of the threaded rod 60 is provided with a head 76 that is disposed between the pin 72 and the underside of the support 58. By manipulating a handle 78 at the other end of the threaded rod, the support 58 will become pivotally adjusted about the pivot 52, the yoke 62 sliding along the rods 68 and 70 to prevent binding of the parts.

According to the present invention, the concavity of the cut may further be varied by vertically adjusting the cutter 8. The cutter 8 is carried at one end of a horizontally disposed shaft 80 that is mounted in ball bearings 82 and 84 carried by a bracket 86. The bracket 86 has two vertically disposed recesses 88 that align with corresponding recesses 90 in the frame of the machine and in which aligned recesses are mounted guides 92 for guiding the vertical movement of the bracket 86. Such vertical movement is effected by a screw 94 that is vertically threaded in an overhanging arm 96 of the frame and that is swiveled to a portion 98 that projects out from the bracket 86. Bolts or tightening screws 100 secure the bracket in vertically adjusted position on the frame. The screws 100 extend through vertically elongated openings 102 in the frame and are threaded in the bracket. The vertical adjustment of the bracket effects the adjustment, as a unit, of the shaft 80, and the cutter 8, the fly wheel 104 and the pulley 106 mounted thereon.

It is further necessary to adjust the position of the heel-block holder on the carriage, so that the cutter shall not cut too far longitudinally into the heel block. As is explained in the above-named patent, the rod 68 is freely slidable through a bore in the heel-block holder and the rod 70 is threaded in another bore of the holder. By rotating the threaded rod 70, therefore,—using a handle 108 for such purpose—the heel-block holder may be longitudinally adjusted of the carriage. But there is a tendency for the heel-block holder to bind against the rods 68 and 70. This is prevented, according to the present invention, by providing the holder with two interlocked tubes 110 and 112 between which is mounted an internally threaded split sleeve 114. As shown in Fig. 4, the tubes 110 and 112 are detachably locked together by means of screw threads 116 and the sleeve 114 is maintained in place by shoulders 118 and 120 provided upon the tubes 110 and 112, respectively. The rod 70 is threaded in the sleeve 114, and fits more or less snugly in the tubes 110 and 112, but without binding.

The cutter is driven at very high speed

through a belt 122 that passes over the pulley 106 and that is driven from an electric motor 124. As it is desired to actuate the carriage from the same motor, through the shaft 80, and as the carriage must be driven at considerably lower speed, it is necessary to provide a speed-reducing means. A small pulley 126 at one end of the shaft 80 drives a belt 128 that extends over a large pulley 130. A tension roll 132 (Fig. 3) takes up the slack in this belt 128 that is introduced by the before-described adjustments of the cutter. The shaft 134 of the pulley 130 is provided with a smaller pulley 136 that, through a belt 138, drives a larger pulley 140 on a shaft 142. This shaft is provided with a small pulley 144 for driving a large pulley 146 through belt 148. A clutch 150 connects the pulley 146 with the driving shaft 152 that actuates the carriage through an eccentric 154 and a link 156.

The clutch is automatically caused to couple the pulley 146 to the shaft by the rod 68, acting through a bell-crank lever 158 and a reciprocating rod 160 that is directly connected to the clutch at 162. The rod 68 is rendered effective to actuate the clutch when it is actuated forward longitudinally of the carriage by the operator at the cross bar 164 to clamp the jaws 4 and 6 together upon a heel block interposed therebetween. When the cross bar 164 is actuated forward, it carries with it both the rods 68 and 70, and also the support 58. This causes the tails 166 and 168 of the jaws 4 and 6, respectively, to engage cam rollers 170 that, acting in opposition to the spring 172, causes the jaws 4 and 8 to clamp the heel block. The same movement of the cross bar 164 that clamps the jaws together, therefore, also drives in the clutch.

The clutch is positively disconnected, according to the present invention, as soon as the carriage has performed its two above-described operations, by a cam 174 that rotates with the shaft 38 to engage a pin 176 on one end of a lever 178 that is immediately pivoted at 180 and the other end of which slidably engages the rod 160 at 182 to return the latter to its initial position. At the same time, another cam 184 on the shaft 38 engages a lever 186 that is pivoted at 188 and that, through a link 190, retracts the cross bar 164 to cause the opening of the clamp jaws 4 and 6. The heel-block holder being thus returned towards the operator near the cross bar 164, and the clamp jaws being open, the heel block may be removed, a new heel block inserted, and the operation repeated.

It will be understood that the invention is not restricted to the exact embodiment thereof that is illustrated and described herein, but that modifications may be made without de-

parting from its spirit and scope, as defined in the appended claims.

What is claimed is:

1. A machine for cutting a concave groove in the top of a block having, in combination, a concaving cutter, means for holding a heel block, means for reciprocating the holding means to two predetermined positions and for rendering the holding means ineffective when occupying one of the predetermined positions, and for rendering the holding means effective at the second predetermined position, the holding means being adapted to present the top of the heel block to the action of the cutter in the second predetermined position, whereby the cutter will produce a concaving cut in the top of the heel block when the holding means occupies the second predetermined position, and means for adjusting the cutter towards and from the second predetermined position to vary the concaving cut produced in the top of the heel block by the cutter.

2. A machine for concaving heel blocks having, in combination, a horizontally disposed shaft, a rotatable concaving cutter mounted on the shaft, means for holding a heel block, means for actuating the holding means horizontally to actuate the heel block under and into the cutter, whereby the concaving cutter will produce a concaving cut in the top of the heel block when the heel block is actuated under and into the cutter, and means for adjusting the shaft vertically to vary the concaving cut produced in the top of the heel block by the cutter.

3. A machine for concaving heel blocks having, in combination, a concaving cutter, a carriage, means mounted on the carriage for holding a heel block, the carriage being adapted to be actuated to move the heel block towards and from the cutter, whereby the concaving cutter is adapted to produce a concaving cut in the heel block when the heel block is actuated towards the cutter, means for pivotally adjusting the holding means on the carriage, and means for adjusting the cutter towards and from the path of movement of the carriage, the two last-named means being adapted to vary the concaving cut produced by the cutter.

4. A machine for cutting a concave groove in the top of a block having, in combination, a concaving cutter, a carriage, means mounted on the carriage for holding a heel block, means for actuating the holding means to clamp a heel block, a lever connected with the actuating means, the carriage being adapted to be reciprocated to move the heel block towards and from the cutter to present the top of the heel block to the action of the cutter and to withdraw it therefrom, whereby the concaving cutter is adapted to produce a concaving cut in the top of the heel block when the top of the heel block is presented

to the action of the cutter, means for engaging the lever to cause an unclamping of the heel block after the heel block has been concaved by the cutter, and means for adjusting the cutter.

5. A machine for concaving heel blocks having, in combination, a concaving cutter, a carriage, means mounted on the carriage for holding a heel block, means for actuating the holding means to clamp a heel block, means controlled by the actuating means for actuating the carriage to move the heel block towards and from the cutter along a plurality of paths of movement, whereby the concaving cutter is adapted to produce a concaving cut in the heel block when the heel block is moved towards the cutter, means controlled by the last-named means for rendering the carriage-actuating means ineffective, and means for adjusting the cutter.

6. A machine for cutting a concave groove in the top of a block having, in combination, a frame, a bracket, bearings carried by the bracket, a shaft mounted in the bearings, a rotatable concaving cutter mounted on the shaft, means for adjusting the bracket on the frame, means for securing the bracket to the frame in adjusted position, and means for holding a heel block, the holding means being adapted to be reciprocated towards and away from the cutter to present the top of the heel block to the action of the cutter and to withdraw it therefrom.

7. A machine for concaving heel blocks having, in combination, a frame, a bracket, ball bearings carried by the bracket, a shaft mounted in the bearings, a rotatable concaving cutter mounted on the shaft, a fly wheel mounted on the shaft, a pulley mounted on the shaft, a belt for driving the pulley, means for tensioning the belt, means for adjusting the bracket on the frame, means for securing the bracket to the frame in adjusted position, and means for holding a heel block, the holding means being adapted to be actuated towards and away from the cutter, whereby the concaving cutter is adapted to produce a variable concaving cut in the heel block when the holding means is actuated towards the cutter.

8. A machine for concaving heel blocks having, in combination, a concaving cutter, a carriage, means mounted on the carriage for holding a heel block, means for actuating the holding means to clamp a heel block, a lever connected with the actuating means, means controlled by the actuating means for actuating the carriage to move the heel block towards and from the cutter along a plurality of paths of movement, whereby the concaving cutter is adapted to produce a concaving cut in the heel block when the heel block is moved towards the cutter, means controlled by the last-named means for rendering the carriage-actuating means ineffective.

tive, means for engaging the lever to cause an unclamping of the heel block after the heel block has been concaved by the cutter, and means for adjusting the cutter towards and from the path of movement of the carriage to vary the concaving cut produced by the cutter.

9. A machine for concaving heel blocks having, in combination, a concaving cutter, a carriage, a rod mounted on the carriage, means mounted on the rod for holding a heel block, means controlled by a movement of the rod for actuating the holding means to clamp a heel block, means for actuating the carriage to move the heel block towards and from the cutter, whereby the concaving cutter is adapted to produce a concaving cut in the heel block when the heel block is moved towards the cutter, a clutch between the carriage-actuating means and the carriage, means engaged by the rod during its said movement for rendering the clutch effective, means controlled by the movement of the carriage for rendering the clutch ineffective, and means for adjusting the cutter.

10. A machine for cutting a concave groove in the top of a block having, in combination, a shaft, a rotatable concaving cutter mounted on the shaft, a carriage, means mounted on the carriage for holding a heel block, means for driving the shaft at relatively high speed, means comprising speed-reducing means driven from the shaft for reciprocating the carriage to move the heel block towards and from the cutter at relatively low speed to present the top of the heel block to the action of the cutter and to withdraw it therefrom, whereby the concaving cutter is adapted to produce a concaving cut in the heel block when the top of the heel block is presented to the action of the cutter, a clutch for connecting the carriage to its actuating means, means controlled by a movement of the carriage for rendering the clutch effective, and means operable after the heel block has been concaved for rendering the clutch ineffective.

In testimony whereof, I have hereunto subscribed my name.

50 WESLEY J. SHAW.
